UNITED STATES PATENT OFFICE.

FREDERICK C. ECKELMAN, OF NEW YORK, N. Y.

PERMUTATION-LOCK.

1,178,843.

Specification of Letters Patent. Patented Apr. 11, 1916.

Application filed June 25, 1915. Serial No. 36,370.

To all whom it may concern:

Be it known that I, FREDERICK C. ECKELMAN, a citizen of the United States, residing at New York, in the county of New York 5 and State of New York, have invented new and useful Improvements in Permutation- Locks, of which the following is a specification.

This invention relates to permutation locks and it consists in the novel features 10 hereinafter described and claimed.

An object of the invention is to provide a lock mechanism of simple structural arrangement especially adapted to be used 15 upon automobiles for the purpose of preventing the use of the machine by an unauthorized person. Although the lock is especially adapted to be used as just above indicated, it may by slight variation be used 20 to advantage upon satchels, handgrips or other receptacles of similar nature.

With the above objects in view the lock comprises a casing in which is pivotally mounted a lever provided with pins. Slotted tumblers are turnably mounted in the 25 casing for rotation about an axis common to both and the said tumblers are turnable independent of each other. When the slots in the tumblers are brought into the paths 30 of movement of the pins carried by the lever, the said lever may be swung whereby it may serve as means for releasing the lock. The tumblers are connected with supports which are turnable independent of each 35 other and means are provided for adjustably connecting each tumbler with its respective support so that the combination of the lock may be varied at will.

In the accompanying drawings: Figure 1 40 is a side elevation of the lock. Fig. 2 is an edge elevation of the same. Fig. 3 is a vertical sectional view of the same cut on the line 3-3 of Fig. 5. Fig. 4 is a front elevation of the lock with the forward plate 45 of the casing removed. Fig. 5 is a transverse sectional view of the lock. Fig. 6 is a front elevation of a dial plate used in the lock. Fig. 7 is an edge elevation of the same. Fig. 8 is a front elevation of another 50 dial used in the lock. Fig. 9 is an edge elevation of the dial shown in Fig. 8. Fig. 10 is a front elevation of the lever used in the lock. Fig. 11 is an edge elevation of the said lever. Fig. 12 is a front elevation of

one of the means for adjustably securing 55 the tumbler with relation to its support. Fig. 13 is an edge elevation of the means shown in Fig. 12. Fig. 14 is a side elevation of one of the tumblers. Fig. 15 is a transverse sectional view of the tumbler. Fig. 16 is a perspective view of a block used in the lock structure.

The lock includes a casing 1 which is normally closed at its forward side by a detachable plate 2. The casing 1 may be 65 of any suitable design or pattern, and as shown in the drawings it is in the form of a flat wedge-shaped body. A post 3 is mounted in the casing 1 and a lever 4 is fulcrumed upon the said post. The lower 70 portion of the lever 4 passes through an opening 5 provided at the lower edge of the casing 1, and the said lever is provided at its lower end with a knob 6 of any suitable design or pattern. The lever 4 is provided 75 at one side with a cam 7 which surrounds the post 3. The lever 4 also carries at its upper end and at the opposite sides of the post 3 pins 8.

As shown in Figs. 4, 5, 10 and 11 the 80 lever 4 is provided at its intermediate portion with an outstanding resilient tongue 9, having at its free end portion a detent 10. The casing 1 is provided at its lower portion with sockets 11, 12 and 13, in which the 85 detent 10 may engage when the lever 4 is swung. When the lock is used upon an automobile or similar machine which necessitates the use of an electric current for operating the spark plug or similar device, the 90 socket 13 may be connected with the magneto, the socket 11 may be connected with the battery while no electrical connection whatever is made with the socket 12. Therefore, when the lever 4 is swung to bring the 95 detent 10 into the socket 11, the electric current is established between the battery and the sparking plug. On the other hand, if the lever 4 is swung to bring the detent 10 in the socket 13 an electric current is established between the magneto machine and the 100 spark plug. When the detent 10 is in the socket 12 electric current to the spark plug is interrupted. Therefore the lever may serve as an electric switch.

A shaft 14 is turnably mounted in the upper portion of the casing 1 and is provided at its outer end with a knob 15. A

dial 16 is fixed to the shaft 14 and the upper portion of the said dial is exposed through an opening 17 provided at the upper end of the plate 2. Tumblers 18 and 19 are mounted upon the shaft 14 and as these tumblers are of the same size and pattern a description of one will answer for both. Each of the said tumblers is provided at its side with a recess 20 and the said tumblers are provided at the wall of the recess 20 with inwardly disposed teeth 21. The tumblers are further provided with notches 22 which enter the said tumblers from the outer edges thereof as best shown in Figs. 3 and 14 15 of the drawings. Disks 23 and 24 are mounted upon the shaft 14 and are received in the recesses 20 of the tumblers 18 and 19 respectively. The disks 23 and 24 are provided with peripheral teeth 25 which engage 20 with the teeth 21 of the tumblers 18 and 19, whereby the said disks and tumblers are secured with relation to each other. The disk 23 is fixed by means of pins 26, or other suitable means, to the shaft 14, while 25 the disk 24 is loose upon the shaft 14. A dial member 27 is journaled upon the shaft 14 and the upper portion of the said dial member 27 is disposed above the upper edge of the casing 1 as best shown in Figs. 4 and 30 5 of the drawings. The dial member 27 is provided at its side with a recess 28 in which the dial 16 snugly fits. Pins 29 connect the dial member 27 with the disk 24, consequently the said dial member 27 may be 35 used for turning the tumbler 19, while the shaft 14 may be used for turning the tumbler 18. A block 30 is loosely mounted upon the cam 7 of the lever 4 and the upper surface of the said block is normally spaced 40 below the peripheries of the tumblers 18 and 19 as best shown in Fig. 3 of the drawings. The dial members 16 and 27 are provided at their front faces with suitable graduations or numbers as shown in Fig. 4 of the 45 drawings.

The operation of the lock is as follows: Assuming that the person who is operating the lock is familiar with the combination, the knob 15 is grasped and the shaft 14 is 50 turned, whereby one of the numbers of the combination upon the dial 16 is brought to view through the opening 17. As the shaft 14 is turned the tumbler 18 is turned by the disk 23 so that the notches 22 in the tumbler 55 18 are brought into the paths of movement of the pins 8 carried by the lever 4. The operator then turns the dial member 27 until the other number of the combination is brought to view through the opening 17. 60 During the turning movement of the dial member 27 the disk 24 is turned which in turn rotates the tumbler 19, whereby the notches 22 of the said tumbler are brought into the path of the movement of the pins 65 8. When the notches 22 of both of the

tumblers 18 and 19 are in the paths of movement of the pins 8 upon the lever 4, the said lever 4 is free to be swung in either of two directions and thus an electric current may be established as hereinbefore indicated, or in the event that the lever is used for releasing other parts, of a mechanical lock (not shown), the desired end is attained.

Should an attempt be made to operate the 75 lock by one who is unfamiliar with the combination, it is apparent that considerable difficulty would be experienced in properly positioning the tumblers 18 and 19 whereby their notches are brought into the paths of 80 movement of pins 8 and until the said notches are brought into the said paths, the lever cannot be swung sufficiently to release the lock mechanism. Should such an unauthorized person attempt to manipulate the 85 lock to discover the combination by the clicking sound thereof, he will be frustrated in the attempt for the reason that when the lever 4 is swung the cam portion 7 thereof moves the block 30 up into contact with the 90 peripheries of the tumblers 18 and 19, and prevents their further manipulation. Therefore there is nothing to guide the said person by the sound produced by striking the pins against the peripheries of the tumblers. 95 It is, of course, understood that when the notches in the tumblers are properly positioned in the paths of movement of the pins and when the cam portion 7 is turned, the 100 block 30 is brought up into contact with the peripheries of both of the tumblers 18 and 19, and serves in part to hold the said tumblers against turning movement while the pins 8 move along the notches 22 thereof.

If the combination is properly set the 105 pins will have free passage into the slots in disks and the lever 4 will be free to operate. If the combination is not properly set the slots 22 will not be in the paths of movement of the pins 8 and hence the lever 4 can 110 be swung only to such an extent as to cause the cam 7 to move the block 30 into engagement with the peripheries of the disks 18 and 19 and thus the said disks cannot be turned until the lever 4 is returned to its 115 central or normal position. This prevents a person from "feeling" the pins into the slots. It is also apparent that by removing the front plate 2 from the casing 1 and by removing the shaft 14 and a lever 4 from 120 the casing 1, the tumblers 18 and 19 may be adjusted upon their respective disks and placed back in the lock casing, thus providing means for changing the combination of the lock at will.

From the above description taken in conjunction with the accompanying drawing, it will be seen that a permutation lock of simple and durable structure is provided and that the parts may be easily manipu- 125 130

lated to establish an electric current or for permitting a receptacle to which the lock is applied to be opened.

Having described the invention what is 5 claimed is:—

A permutation lock comprising a casing, a lever pivoted in the casing and having a cam, pins carried by the lever, notched tumblers turnably mounted in the casing and 10 lying in the paths of movement of the pins,

and a block loosely mounted upon the cam of the lever and engageable with the tumblers when the lever is swung.

In testimony whereof I affix my signature in the presence of two witnesses.

FREDERICK C. ECKELMAN.
